UNITED STATES PATENT OFFICE

115,299

DESIGN FOR A TENSION WRENCH

Arthur E. Price, Jackson, Mich., assignor to
Hinckley-Myers Company, Jackson, Mich.

Application March 1, 1939, Serial No. 83,282

Term of patent 7 years

To all whom it may concern:

Be it known that I, Arthur E. Price, a citizen of the United States, residing at Jackson, in the county of Jackson and State of Michigan, have invented a new, original, and ornamental Design for a Tension Wrench, of which the following is a specification, reference being had to the accompanying drawing, forming part thereof.

In the drawing:

Figure 1 is a side elevational view of a tension wrench showing my new design; and

Fig. 2 is a perspective view.

The ornamentation shown on the handle is intended to cover the entire surface of the handle.

I claim:

The ornamental design for a tension wrench, as shown and described.

ARTHUR E. PRICE.
